(57) **CLAIM**

I claim, the ornamental design for an epinephrine auto injector carrier, as shown and described.

DESCRIPTION

FIG. 1 is a perspective front view of an epinephrine auto injector carrier according to the present invention:

FIG. 2 is a perspective rear view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.
